GARMENT

Harry J. Leon, Hartford, Conn.

Application March 27, 1943, Serial No. 480,795

1 Claim.

(Cl. 2—71)

My invention relates to the class of garments adapted more especially for feminine wear and which embodies a combination of pants and skirt, and an object of my invention, among others, is the construction of a garment of this type in which the pant or trouser effect shall be obscured so that the garment shall have the general appearance of a dress complete including a waist and skirt.

One form of a garment embodying my invention and in the construction and use of which the objects herein set out, as well as others, may be attained is illustrated in the accompanying drawing, in which—

Figure 1 is a front view of a garment embodying my invention.

Figure 2 is a back view showing the garment partially open.

Figure 3 is a front view showing the garment partially open.

Figure 4 is a view in cross section on a plane denoted by the broken line 4—4 of Fig. 1.

Fig. 5 is a view in cross-section on a plane denoted by broken line 5—5 of Fig. 1.

My improved garment herein illustrated and described is made for the purpose of enabling the wearer to present an appearance of being dressed in strictly feminine attire embodying a dress comprising a waist and a skirt, while permitting freedom of movement as allowed by a masculine garment comprising trousers and without undue exposure of under garments, thereby enabling the wearer to always be within the strictest bounds of propriety, my improved garment, as shown in the drawing herein, comprising a dress including a waist 6 that may be made in any approved form, but preferably being an integral part of the skirt, although this is not absolutely essential, the principal feature of the invention residing in the lower portion of the garment which is made to all appearances closely resembling a skirt, the garment including a waist and a skirt and having an opening 7 at the front extending from a neck 8 to the bottom of the skirt, which opening may be closed at the waist and secured as by means of buttons and button holes 9 or other fastenings of a similar nature common to garments. The fastenings are omitted at the lower part of the opening as shown in Fig. 3, thereby creating a gap 10 which may be freely open to provide freedom of movement of the leg of the wearer. An opening 11 at the back of the skirt extends from the bottom of the latter upwardly, as shown herein for about one-half of the length of the skirt forming a freely

open gap 12 to provide for freedom of movement of the other leg of the wearer, as in the case of the front opening 7. This opening may be closed at the top as by stitching 21.

10 A pant flap 13 is secured inside of the front of the skirt at one side and a short distance back from the edge of the opening 7, this flap being of a length substantially that of the skirt and a companion flap 14 is secured to the inside of the back of the skirt at one side of the opening or gap 12, in the same manner as the flap 13, the two flaps being extended toward each other and secured together at their edges as by stitching. When thus stitched together these two flaps

15 form the inside of a leg covering 22.

The description thus far has been for one side of the garment. The other side of the garment is substantially of the same construction and comprises a pant flap 15 secured to the back of

20 the front part of the skirt a short distance away from the edge of the opening 7 and another similar flap 16 secured to the inside of the back of the skirt a short distance from the edge of the opening 11 and extending toward the flap

25 15. The meeting edges of the two flaps 15—16 are secured together and thereby constitute a leg covering 23 similar to and located opposite the cover formed by the flaps 13—14. The two flaps are preferably secured together at a meeting point 30 at the upper ends of the flaps forming a crotch 17 as in the ordinary form of pant construction.

The front of the skirt is made with gores 18 as shown in Fig. 1, on opposite sides of the opening 7, and especially on that side comprising the greatest expanse of the front while the back is composed of two pieces 19—20 on opposite sides of the gap 12, one of said pieces overlying the other for such distance back from the gap 12 to present when in normal condition a continuous skirt back, the opening 11 being normally closed.

As will now have been seen the main feature of the garment disclosed herein and comprising my invention consists of a skirt comprising the outside of the lower part of the garment and having the gaps or openings 10—11 at the front and back to provide for freedom of movement of the limbs of the wearer and in order to shield the limbs of the wearer the coverings 22—23 are provided with their opposite edges secured to the inside of the front and back of the skirt and extending across the opening between the front and back of the skirt at a point inside of the limbs of the wearer of the skirt.

It will be understood that the thickness of the material in the sectional view is exaggerated and

that regular ordinary stitching is employed in securing the pieces together.

I claim:

A dress comprising a waist and a skirt attached to the bottom of the waist and extending downwardly therefrom, said skirt comprising a pair of flaps simulative of a dress and a pair of inner flaps cooperating with the skirt flaps to simulate trousers legs with the latter normally confined within and hidden by the skirt flaps, said skirt 10 being characterized by one skirt flap having one

vertical free edge positioned in front of one leg portion and extending around the other leg portion with the other vertical edge positioned rearwardly of the other leg, one of said inner flaps being attached at its rear vertical edge to the rear vertical edge of said skirt flap and having its other vertical edge attached to the front portion of said skirt flap substantially in line with the rear vertical edge attachment, and a reversed like formation at the other side of the dress.

HARRY J. LEON.
